UNITED STATES PATENT OFFICE

OTTO R. WOLF, OF RIVER FOREST, ILLINOIS, ASSIGNOR TO THE TRIBUNE COMPANY, OF CHICAGO, ILLINOIS, A CORPORATION OF ILLINOIS

PRINTING PRESS

Application filed January 3, 1931. Serial No. 506,344.

This invention relates to the art of printing and particularly to an improvement in intaglio printing presses designed especially for use in multi-color work.

5 In my Patent No. 1,784,037, issued December 9, 1930, I have shown a press in which printing in a plurality of colors is effected by the use of a series of narrow width printing cylinders, in combination with one or more 10 full width printing cylinders, the narrow width cylinders being arranged to make an impression upon a particular part of the web independently of the printing of the remaining portions of the web. The use of the narrow 15 width cylinders, each of which is adjustable independently of the other members of the series, greatly increases the flexibility of the press from the standpoint of color variation, and also simplifies the work of obtaining 20 accurate registration of the impressions produced by the several units of the press.

While the use of individual narrow width printing cylinders is desirable from the 25 standpoint of color variation obtainable, it is not wholly satisfactory in practice due to the difficulty encountered in removing ink from the ends of the cylinder. The scraper knife engages the cylindrical face of the cylinder 30 but does not remove the ink from the ends of the cylinder, with the result that a mark is frequently made on the web at the end of the cylinder. It is for this reason that it is necessary to use printing cylinders which are 35 long enough to extend beyond the edges of the widest web that is to be printed.

One of the important objects of my invention is to provide a press for printing a plurality of colors in intaglio in which only full 40 width printing cylinders are used, the flexibility obtainable by the use of the narrow width cylinders, as disclosed in my previous application hereinbefore referred to, being attained according to my invention, by making 45 provision for the release of the web in the second couple of a color unit to allow the impression made by the first intaglio cylinder to pass through the second couple of the unit without contacting the intaglio cylinder of 50 the second couple.

Other objects and advantages of my invention will be apparent as I proceed with my specification, which, taken in connection with the accompanying drawings, discloses a preferred embodiment thereof.

55

In the drawings:

Fig. 1 is a diagrammatic view of a multi-color intaglio press embodying the invention;

Fig. 2 is a plan view showing in diagrammatic form the arrangement of the couples in the several units of the press;

Fig. 3 is a transverse view, partly in section, showing the mounting of one of the couples in the press frame; and

Fig. 4 is a detail section, taken on the line 4—4 of Fig. 3, and illustrating the means for obtaining radial adjustment of the intaglio cylinder.

Referring to the drawings, and particularly to Fig. 1, the press comprises, in the embodiment shown; four color units, indicated generally by the numerals 1, 2, 3 and 4, the first three including separate couples for making an impression on a portion of the 75 width of the web and the fourth including a single couple for printing over the full width of the web; a color unit 5 consisting of a single couple for printing the opposite side of the web; a series of drying cylinders 6 interposed between the successive units of the press; and a folding mechanism 7 for reducing the web to page form.

The web 8 is taken from a supply roll 9 over a guide roller 11 from which it passes through the first color unit 5 to a second guide roller 12, from which point it passes upwardly around the first of the drying cylinders 6. From this point the web is alternately threaded in order through the color 90 units 1, 2, 3 and 4 and over the intervening drying cylinders 6 to the folding mechanism 7, the guide rollers 13 being positioned at regular intervals along the path of the web to support it in the proper position relative to the printing and drying cylinders. Each of the intaglio cylinders is provided with an individual inking fountain 14 and a scraper knife 15 for removing excess ink from the surface of the cylinder. Any convenient type 100

of fountain and scraper knife may be employed to control the supply of ink to the intaglio cylinders.

Referring now to Fig. 2, the several color units 1-5 are arranged, according to my invention, to print a series of composite impressions on the web 8 much as in the manner previously attained by the use of narrow width intaglio cylinders. This is accomplished by 10 off-setting the impression cylinder in the second couple of each of the units which prints a portion of the width of the web, to allow the impression of the first couple of the unit to pass through the unit without contacting 15 the intaglio cylinder of the second couple.

The first unit 5 consists of an etched or intaglio cylinder 17, and an impression cylinder 18, between which the web passes to receive an impression of the design of the cylinder 17. The cylinder 17 prints across the full width of the web, on the outside, that is, on the side opposite the one to be printed in several colors in the following units. In the embodiment shown unit 5 prints the outside 25 of the sheet in brown, the cylinder 17 being etched to print the design 19 on the upper half of the web and the design 20 on the lower half of the web.

The second color unit 1 consists of individual couples having intaglio cylinders 21 and 22 and corresponding impression cylinders 23 and 24. The cylinder 21 is etched to print the lower half of the web 8 and the cylinder 22 is etched to print the upper half 30 of the web. It will be apparent that inasmuch as a drying cylinder cannot be interposed between the couples of unit 1, it is necessary to provide means for preventing contact between the impression printed by the cylinder 21 and the face of the cylinder 22. According to my invention the impression cylinder 24 of the second couple is off-set or under-cut, as indicated at 25, to provide clearance for allowing the impression of the first 40 couple to pass through the second couple without contacting the cylinder 22. By thus reducing the diameter of the cylinder 24 over the area of the web which is printed upon by the cylinder 21, I am able to print designs 45 on both the upper and the lower halves of the web in a single color unit without using narrow width cylinders. The amount of offset on the cylinder 24 need not be more than $\frac{1}{2}$ of an inch, the object being merely to 50 provide sufficient clearance to prevent contact of the impression of the first couple with the face of the second intaglio cylinder. The off-set shoulder joining the portion of the cylinder of reduced diameter and the full 55 diameter portion is preferably tapered to avoid a sharp edge. It is not necessary to have an off-set in the first couple of the unit inasmuch as the impression of the previous 60 unit has been dried by the drums 6 by the time they reach the succeeding units. I have 65

found that there is no tendency whatever for the paper to be thrown out of alignment by reason of this off-setting in the second couple of the color unit. The first couple engages the full width of the web and prevents the off-set in the second couple from affecting the aligned position of the web. The succeeding color units 2 and 3 are similar in construction to unit 1, each being provided with individual couples for printing on the upper and lower halves of the web. The last color unit 4 consists of a single couple comprising an intaglio cylinder 26 and an impression cylinder 27. In the embodiment shown this unit prints in black over the full width of the web.

The operation of the press will be readily understood by reference to Fig. 2. The colors printed in the several units are indicated on the figure and are in order: brown, yellow, red, blue, and black. It will be understood that the showing of the designs on the web in this figure is diagrammatic only, both the designs 19 and 20 which are printed in unit 5 on the outside of the sheet, and the designs subsequently printed on the inside of the sheet, being shown in full lines.

As the lower half of the web passes between the cylinders 21 and 23 forming the first couple of unit 1, it receives a design 65 in yellow which is formed by the etching on the lower half of the intaglio cylinder 21. Although this design is still wet it passes between the cylinders 22 and 24 of the second couple without injury inasmuch as contact with the cylinder 22 is avoided by the offset on the cylinder 24. In passing between the cylinders 22 and 24 the upper half of the web similarly receives two designs 66 and 67, in yellow, which are formed by the etching on the upper half of intaglio cylinder 22. The design 65 may either be of the same shade of yellow as the designs 66 and 67, or of a different shade, inasmuch as separate ink fountains are provided for each couple of the unit.

As the web passes between the cylinders 21 and 23 of the second color unit, which is the red unit, it receives a design 68 in red, which is formed by the etching on the lower half of the intaglio cylinder 21 of the first couple. In passing between the cylinders 22 and 24 of the second couple the upper half of the web is given a design 69 in red, and also two orange designs 71 and 72, the design 71 being formed by superposing the red on the yellow design 66, and the design 72 being similarly formed by superposing the red on the lower portion of the yellow design 67. It will be noted that the red color printed on the upper and lower halves of the web need not be of the same shade inasmuch as each couple of the red unit is provided with a separate ink fountain.

In the third color unit, which is the blue unit, the lower half of the web in passing

between the cylinders of the first couple is given a design 73 in blue, this design avoiding contact with the intaglio cylinder of the second couple by reason of the offset in the 5 impression cylinder of said couple. The upper half of the web in passing through the cylinders of the second couple of this unit receives a design 74 in blue, and a design 75 in black, the latter being formed by superposing blue on the orange design 71. The same shade of blue need not be printed in the separate couples of this unit, there being 10 separate ink fountains for each couple.

In passing through the last unit 4, which 15 is the black unit, both halves of the web are printed at the same time, inasmuch as this unit consists of a single couple which prints over the full width of the web. In this unit the lower half of the web is given an outline 20 76 in black. Similarly the upper half of the web is given an outline 77 in black.

If desired, instead of employing a single couple in unit 4, as shown, a pair of couples 25 may be provided as in units 1-3. Also one or more of the latter units may be replaced by 30 a unit like unit 4 in case it is desired to print in one of the colors over the full width of the web. The particular combination of the several units may be varied as desired to meet the class of work for which the press is to be used.

While the designs illustrated have been indicated merely as rectangular strips, it will be noted that the particular outline of the design 35 may be formed to illustrate any desired type of subject matter. This sequence of color printing may be considered as a typical example of the work which may be attained on a press constructed according to my invention. Designs of different subject matter and having different color combinations are produced on the opposite halves of the web by independent printing operations in the units 1, 2, and 3. Printing in different colors, 40 or in different shades of the same color, may be accomplished in a single unit just as in the case of the use of the narrow width intaglio cylinders. The design produced on the upper half of the web includes the colors: 45 yellow, orange, red, black and blue, one black being an original one, and the other being formed by the combination of yellow, red and blue. The design on the lower half of the web contains an original black, and the three elementary colors, yellow, red and blue. The example illustrates the color variation 50 which may be obtained by the use of the press.

In the embodiment shown in the drawings 55 60 the outside of the sheet is illustrated as being printed in a single color, this being effected in unit 5. By substituting for unit 5 a series of color units such as units 1, 2, and 3, the outside of the sheet could be printed in a 65 plurality of colors in the same manner as

described for the printing of the inside of the sheet.

Inasmuch as all of the cylinders in the press are full width cylinders, the mechanism for obtaining longitudinal and radial adjustment of the cylinders may be of any standard type now well known in the art. One form of such mechanism, as applied to the second couple of one of the color units, is shown in Figs. 3 and 4. The shaft 36 for supporting 70 the intaglio cylinder 22 is journaled at its opposite ends in bearings 37 carried by the columns 38 of the press frame.

The mechanism for obtaining longitudinal adjustment of the cylinder 22 is shown in 75 the left-hand portion of Fig. 3. This mechanism comprises; a threaded shaft member 39, rotatably supported in a bracket arm 41 which is secured to the column 38; a traveling block 42, slidably mounted upon a rod 43 80 extending parallel to the shaft member 39; and a second block 44 carried on a sleeve 45 which is secured on the projecting end of shaft 36. A nut 46 holds block 44 on the sleeve 45. The blocks 42 and 44 are tapped to receive the 85 threaded shaft member 39. The longitudinal movement of these blocks, effected by turning of the hand wheel 47, serves to shift the cylinder 22 in the bearings 37. This longitudinal adjustment affords means for aligning the 90 etching on the cylinder 22 with the other portions of the design etched on the co-operating cylinders of the other units.

The mechanism for obtaining radial adjustment of the intaglio cylinder 22 is shown 100 in the right-hand portion of Fig. 3, and in Fig. 4. It comprises a circular plate 48, secured to shaft 36 by a key 49, and an annular spur gear 51 supported on the hub of plate 48. The gear 51 is connected to the plate 48 by 105 bolts 52, the inner ends of which are threaded to engage tapped openings in the plate 48. The web portion of gear 51 is provided with arcuate slots 53 to provide for adjustment of the gear 51 on the hub of plate 48. When the radial position of cylinder 22 has been adjusted to obtain correct registry of the etching with the web, the bolts 52 are tightened to hold the cylinder 22 in fixed position relative to the other cylinders of the press. The 110 couple is driven through gear 51 which connects with the gears which drive the adjacent couple of the unit and with gears which connect with the main drive shaft of the press. This drive mechanism is well known in the 115 art and forms no part of the present invention.

The impression cylinder 24 is yieldingly and adjustably supported from the press 120 columns 38 to permit control of the pressure applied to the web. In the embodiment shown the shaft 54, which supports the impression cylinder 24, is supported at its opposite ends in hangers 55. Each of the hangers 55 is supported from a bracket 56 which 125

is secured by suitable bolt connections to the adjacent column 38 of the press frame. The connection between the bracket 56 and the hanger 55 is shown in detail in the upper left-hand portion of Fig. 3. A bolt 57 extends centrally through a sleeve 58 and is secured at its lower end in the hanger 55, the upper end of said bolt being provided with lock nuts 59 which rest on the upper end of sleeve 58. The lower end of bolt 57 has screw-threaded engagement with a bushing 61 which has free sliding movement in a counterbore 62 formed in the lower end of sleeve 58. A coil spring 63, interposed between the bushing 61 and the upper end of the counterbore 62, affords a yielding connection between bolt 57 and sleeve 58. The upper portion of sleeve 58 is threaded exteriorly to engage an inferiorly threaded gear wheel 64, the turning of which raises or lowers the sleeve 58 in the bracket 56. The gear wheels 64 at the opposite ends of the cylinder 24 are interconnected by suitable gear and shaft connections to effect simultaneous adjustment of both ends of the impression cylinder.

While I have illustrated the invention as applied to one general arrangement of a multi-color intaglio press, it is to be understood that this general arrangement may be of any desired or known form. Also if it is only desired to use a single color for both couples of a given unit, a single inking fountain may be employed to supply both of the intaglio cylinders.

While I have shown the use of an under-cut impression cylinder in the second couple of units 1-3, to provide the necessary clearance for the impression formed in the first couple, I do not wish to have the invention limited to the use of the under-cut impression cylinder. In some cases it might be preferred to under-cut the intaglio cylinder of the second couple rather than the impression cylinder. If the clearance is provided by reducing the size of the intaglio cylinder a very gradual taper from the undersize portion of said cylinder to the full-size portion would have to be provided so that the scraper knife could engage all portions of the cylinder. When the off-set is provided on the impression cylinder, as shown, there is no particular objection to having a fairly sharp shoulder. Ordinarily, I prefer to provide an off-set on the impression cylinder as shown.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. In a printing press for printing in intaglio, a printing unit comprising a pair of printing couples, each couple including an

impression cylinder and an intaglio cylinder for printing a portion of the width of the web, one of the cylinders of the second couple being under-cut circumferentially over that portion of its length corresponding to the width of the section of the web printed by the first couple to allow said web section to pass through the unit without contacting the cylinders of the second couple. 70

2. In a press for printing in intaglio, a printing unit comprising a pair of printing couples, each couple including an impression cylinder and an intaglio cylinder for printing a portion of the width of the web, one of the cylinders of the second couple being under-cut circumferentially over that portion of its length corresponding to the width of the section of the web printed by the first couple to allow said web section to pass through the unit without contacting the cylinders of the second couple, and inking devices individualized to each couple of said unit. 80

3. In a press for printing in intaglio, a printing unit comprising a pair of printing couples, each couple including an impression cylinder and an intaglio cylinder for printing a portion of the width of the web, the impression cylinder of the second couple being off-set to allow that part of the width of the web bearing the first impression to pass through the unit without contacting the cylinders of the second couple. 90

4. In a press for printing in intaglio, a printing unit comprising a pair of printing couples, each couple including an impression cylinder and an intaglio cylinder for printing a portion of the width of the web, the cylinders of the second couple being shaped to provide clearance between that part of the width of the web bearing the first impression and the face of the second intaglio cylinder. 10

5. In a press for printing in intaglio, in combination: a printing unit for printing on one side of the web, said unit having an intaglio cylinder for printing the full width of the web; and a second printing unit for printing on the other side of the web, said last mentioned unit comprising a pair of printing couples, each of said couples including an impression cylinder and an intaglio cylinder for printing a portion of the width of the web, one of the cylinders of the second couple being under-cut over the portion of the web printed by the first couple to allow the impression of the first couple to pass through the unit without contacting the cylinders of the second couple. 11

6. In a press for printing in intaglio, in combination: a printing unit for printing on one side of the web, said unit having an intaglio cylinder for printing the full width of the web; and a second printing unit for printing on the other side of the web, said 12

last mentioned unit comprising a pair of printing couples, each of said couples including an impression cylinder and an intaglio cylinder for printing a portion of the 5 width of the web, the cylinders of the second couple being shaped to provide clearance between the impression of the first couple and the face of the second intaglio cylinder.

7. In a press for printing in intaglio, in 10 combination: a printing unit for printing on one side of the web, said unit having an intaglio cylinder for printing the full width of the web; a second printing unit for printing on the other side of the web, said last 15 mentioned unit comprising a pair of printing couples, each of said couples including an impression cylinder and an intaglio cylinder for printing a portion of the width of the web, one of the cylinders of the second couple 20 being under-cut over the portion of the web printed by the first couple to allow the impression of the first couple to pass through the unit without contacting the cylinders of the second couple, and inking devices individualized to the couples of said units. 25

In witness whereof, I hereunto subscribe my name to this specification.

OTTO R. WOLF.
